UNITED STATES PATENT OFFICE

GEORGE H. HAMILTON, OF EAST GRAND RAPIDS, MICHIGAN, ASSIGNOR TO AMERICAN
SEATING COMPANY, OF GRAND RAPIDS, MICHIGAN, A CORPORATION OF NEW JERSEY

DESIGN FOR A CHAIR

Application filed March 19, 1931. Serial No. 39,145. Term of patent 3½ years.

To all whom it may concern:

Be it known that I, GEORGE H. HAMILTON, a citizen of the United States, residing at No. 621 Rosewood Ave., East Grand Rapids, in the county of Kent and State of Michigan, have invented a new, original, and ornamental Design for a Chair, of which the following is a specification, reference being had to the accompanying drawing, forming a part thereof, in which:

The figure is a perspective view of the chair, showing my new design.

I claim:

The ornamental design for a chair, substantially as shown.

GEORGE H. HAMILTON.
